UNITED STATES PATENT OFFICE.

LESLIE ASBURY VANDIVER, OF CHICAGO, ILLINOIS.

DESIGN FOR A SHOW-CASE.

42,076.

Specification for Design.

Patented Jan. 2, 1912.

Application filed April 26, 1911. Serial No. 623,524. Term of patent 14 years.

To all whom it may concern:

Be it known that I, LESLIE A. VANDIVER, a citizen of the United States, residing at Chicago, in the county of Cook and State of Illinois, have invented a new, original, and ornamental Design for Show-Cases, of which the following is a specification, reference being had to the accompanying drawing, forming part thereof.

Figure 1 of the drawing is a front elevation of the show case; Fig. 2 is a plan view; and Fig. 3 is a rear elevation.

I claim:

The ornamental design for a show case, as shown.

LESLIE ASBURY VANDIVER.
